BAG HOLDER AND SEWER

Glenn B. Jackson, Newton, Iowa

Application November 23, 1931
Serial No. 576,753

11 Claims. (Cl. 112—11)

The object of my invention is to provide a simple, durable and inexpensive bag holder so constructed that the bag may be easily and quickly placed therein with one end open, in such manner that material may be easily applied, and in connection therewith means for closing the open end of the bag in such manner that it may be easily sewed.

A further object is to provide a bag holder supported on a portable truck in which the bag is supported in a suitable manner for filling, so that the bag may be quickly moved from one position to another for filling and weighing.

A further object is to provide in a bag holder means for closing the open end of the bag after it has been filled, and for automatically pleating the closed end and supporting the pleats in such a manner that a needle may be easily inserted transversely through the folded pleats.

A further object is to provide in a bag holder improved means for closing the open end of the bag and pleating the same; and further improved means for fastening the pleated ends of the bags.

My invention consists in the construction, arrangement and combination of the various parts of the device, whereby the objects contemplated are attained, as hereinafter more fully set forth, pointed out in my claims, and illustrated in the accompanying drawings, in which:

30 Figure 1 is a side elevation of my improved bag holder.

Figure 2 is a detail sectional view taken on the line 2—2 of Figure 1.

Figure 3 is a plan view of the bag holder.

35 Figure 4 is a plan view of the pleating mechanism showing the manner in which the pleats are formed.

Figure 5 is a detail sectional view taken on the line 5—5 of Figure 3.

40 Figure 6 is a detail sectional view taken on the line 6—6 of Figure 4, showing the bag in a released position.

Figure 7 is a diagrammatical plan view showing the bag in closed position before the pleating operation takes place.

45 Figure 8 is a longitudinal sectional view of the needle for sewing the bag.

Figure 9 is a top view of the closed bag showing the manner in which the sewing member is applied.

50 Referring to the accompanying drawings, I have used the reference numeral 10 to indicate the base frame constructed of tubular members 11 and of rectangular formation, said frame 10 being carried by suitable casters 12 to permit

the frame to be moved from one position to another.

Carried by one side of the frame 12 is a pair of upright members 13, the upper ends of which are provided with a horizontal frame portion 60 14. Said frame portion is carried by brackets 15 on the upper ends of the members 13, and comprises side members 16 bolted to the bracket 15 by bolts 17. The forward ends of the members 16 are connected by a cross bar 18. 65

The side members 16 are each provided with a longitudinal slot 19, said slots being designed to support a square shaft 20 having rounded portions 21 at each end, which project through the slot 19. Rotatively mounted in the forward 70 end of the member 16 is a second square shaft 22. Each of said shafts 20 and 22 has a series of what I shall term pleating fingers 23 slidably mounted longitudinally of the shafts.

Supported alternately between the fingers 23 75 are a number of springs 24 for holding the fingers yieldably in separated relation with each other. The fingers 23 of the shaft 20 are supported normally in staggered relation with those of the shaft 22 in the manner clearly illustrated in 80 Figures 3 and 4.

A sleeve 25 is supported between the adjacent frame member 16 and the first fingers 23 of the shaft 21 to properly space the said fingers in staggered relation with those of the opposite 85 shaft. The other end of the shaft 21 is provided with a rock arm 26 having a roller 27 designed to travel on a track 28 secured to the inner face of the adjacent frame member 16 as illustrated in Figure 5. The forward end of 90 the track 28 terminates in a downwardly inclined portion 29.

A tongue 30 has one end pivoted at the point 31 to the frame member 16. The top of the tongue 30 is in line with the top of the track 95 28. One end of the shaft 22 is provided with an arm 32 which extends rearwardly and is provided with a slot 33 for receiving the roller 27. The bottom of the slot 33 is in line with the top edge of the tongue 30. The member 32 also 100 has an upwardly extending portion 34 designed to engage a latch member 35 to support the free end of the member 23 against downward movement. A spring 36 is provided for retaining the latch yieldably against a stop pin 37 and in the 105 path of the upper end of the member 34. The member 35 has an upwardly extending portion 38 for receiving a latch hereinafter described.

The top edges of the inner ends of the fingers 23 are provided with upwardly extending pins 110

39, and also with spring members 40 adjacent to said pins. The parts are so arranged that if the bar 20 is at its outer limit of movement in the slots 19, then the upper end of the bag 41 5 may be applied to a number of the pins 39 and beneath the spring members 40, in such manner as to hold the bag in an open position, illustrated in Figure 3.

The roller 27 prevents the inner ends of the 10 fingers 23 from turning downwardly due to the weight of the bag, while the latch 37 supports the inner end of the fingers on the shaft 22 against downward movement.

By this arrangement it will be seen that different size bags may be threaded on the fingers 23. The bars 21 and 22 are of such length in ordinary practice as to take either small or large bags. The maximum size bag is illustrated in Figure 3, in which case one or more free fingers 20 are provided at the ends of one or both of said shafts 21 and 22, the free fingers being indicated by the numeral 42.

The bottom of the bag is supported on an upwardly and forwardly inclined platform 43, one 25 end of which is pivotally mounted on a transversely arranged shaft 44 carried by the uprights 13. The said shaft 44 is carried in suitable brackets 45 adjustably mounted on the uprights 13 by suitable set screws 46. Means is thus provided for accommodating bags of different lengths.

A spring 47 is provided for supporting the free end of the platform 43 in its elevated inclined position. The rear end of the platform 35 has an upwardly and rearwardly extending lever 48, by means of which the free end of the platform 43 may be oscillated up and down to cause the lower end of the bag to be elevated and lowered and the material within the bag to be packed.

The platform 43 also provides means whereby 45 the bag may be quickly delivered from the holder by simply pushing the upper end of the lever 48 forwardly against the tension of the spring 47, permitting the platform to assume a downwardly inclined position. This takes place, however, after the sewing operation, hereinafter described, has been accomplished.

For moving the bar 20 toward the bar 22 to close the open end of the bag, I have provided in the frame member 10 a rock shaft 49, each end of which is provided with an upwardly extending arm 50, the upper ends of the arms 50 having slots 51 for receiving the rounded portions 21 of the shaft 20. Said arms 50 are supported outside of the frame members 16. One of the arms 50 has an upwardly extending portion 52 designed to carry a latch 53. Secured to one of the arms 50 is a lever 54 extending forwardly and having a pedal 55. The rear end of the lever 54 extends rearwardly from the arm 50 and is designed to engage a spring actuated latch 55a also pivotally mounted to the frame 10, said latch having a rearwardly extending portion 56 designed to be engaged by the operator's foot for releasing the latch from the lever 54.

By this arrangement it will be seen that if the operator's foot is placed on the pedal 55 and the pedal lowered, then the upper ends of the arms 50 will be moved forwardly, carrying with them the bar 21 together with the rear edge of the open end of the bag.

The arms 50 have a rearwardly extending loop portion 57 designed to engage the lower end of the bag as the arm 50 is moved forwardly, and to move it forwardly along the upper surface of

the inclined platform 43, causing the bag to be elevated to compensate for the shortening of the sides of the bag as they are moved inwardly over the upper end of the material therein.

Pivotedly mounted on each side member of the frame 10, to swing laterally is an arm 58. The upper end of each of the arms 58 is provided with a short plate 59. Said plates 59 are designed to engage the outer ends of the sleeve portions of the outer fingers 23 when the bar 20 has been moved toward the bar 22 to such position that the inner ends of the fingers of the bar 20 are substantially in alinement with the inner ends of the fingers of the bar 22, or at a time when the upper edges of the bag assume a closed position, as illustrated in Figure 7.

Each of the arms 58 is provided with a cam 60 designed to be engaged by a corresponding one of the arms 50 as it is moved forwardly in such manner that the arms 50 assume the position where the top of the bag is closed, as shown in Figure 7. Said arms 50 will then engage the cams, causing the upper ends of the levers 58 to be moved inwardly toward each other upon further forward movement of the arms 50, which will cause the fingers 23 to be moved together at the same time the fingers of the shaft 21 pass between the fingers of the shaft 22, and thus cause the upper and adjacent edges of the closed bag to be pleated in the manner shown in Figure 105 4, at which time the latch 53 will engage the upper end of the member 38, as shown by dotted lines in Figure 5.

The rear end of the lever 54 will at this time be engaged by the upper end of the latch 55a to lock 113 the bars 20 and 22 in said closed position. As the bar 20 moves forwardly, the roller 27 travels on the upper surface of the track 28 over the upper surface of the tongue 30 and into the groove 33 of the member 32.

It will be seen by reference to Figures 1 and 6 that each of the fingers 23 is provided with a slot 61, the inner ends of the slots being enlarged, while their outer ends are somewhat contracted.

It will further be seen that when the said bars are at their closed position, as shown by dotted lines in Figure 6, the slots of the two sets of fingers are in alinement in such a manner that a needle may be passed transversely through all 125 of said slots 61, and through the pleats of the upper end of the bag. A needle 62 is provided, having an eye 63 near its pointed end for receiving a hook 64 of a small wire 65, said wire being supported adjacent to one side of the needle as 130 the needle is inserted through the pleats, in such a manner that the wire is carried through the pleats. The free end of the wire is then bent to form a hook to prevent the wire from being moved from the pleats after the needle is removed.

The needle is removed by simply supporting the free end of the wire in one hand and pulling the needle rearwardly to shove the hook 64 to the forward end of the slot 63, after which the wire 140 may be rotated through an angle of about 45°, permitting the needle to be removed.

The hook portion 64 will then retain one of the end pleats of the closed end, while the newly formed hook on the free end of the wire will 145 retain the other end pleat. The bag is then sewed in the manner illustrated in Figure 9.

The operator then places his foot on the member 56, causing the latch 55a to disengage the lever 54. A spring 66 will then cause the levers 150

50 to be moved rearwardly. As soon as the member 52 moves rearwardly, the hook 53 will move the upper end of the member 38 rearwardly and release the member 34 at the time the operator moves the free end of the member 48 forwardly, tilting the platform 43 downwardly, which will permit the weight of the bag to be carried by the fingers 23 and the arm 32, inasmuch as the roller 27 at this time rests in said arm.

10 Further rearward movement together with the weight of the bag will permit the free ends of the arms 26 and 32 to move downwardly and the shafts 20 and 22 to be rotated with the fingers 23 in the position illustrated in Figure 6, at 15 which time the bag will be disengaged from the ends of the pins 39. The roller 27 will move rearwardly at the time the free end of the member 32 is being moved downwardly, causing the said roller to disengage the slot 33 and to pass 20 beneath the pivot 31 of the tongue 30, and upon further rearward movement to engage the inclined portion 29 in such manner that further rearward movement of the arm 52 will cause the roller 27 to ascend the inclined portion and elevate the free end of the tongue 30 and to finally 25 rest on the track 28, causing the shaft 20 to be returned to its normal position.

A spring 67 is provided for returning the shaft 22 to its normal position. A stop 68 is provided 30 for limiting the rearward movement of the member 34 against the action of the spring 67.

Referring to Figure 7 it will be noted that as the upper edge of the bag is moved to a closed position, then the side members 69 of the bag 35 will be bulged outwardly from the outer pins 39. These outwardly extending portions 69 will be pleated in the same manner as that portion on the supporting pins.

I have found by actual practice that unless 40 an inclined platform, such as 43, is provided, then the upper folded edges of the side members 69 would draw downwardly as the side members of the sack are moved together, but by providing the inclined platform, and means for moving the lower end of the bag forwardly and upwardly, then the upper edges of these side members are elevated sufficiently to permit the entire upper edge of the folded bag to assume a substantially straight line when in the position shown 45 in Figure 7.

50 Thus it will be seen I have provided a bag holder of simple, durable and inexpensive construction, provided with means whereby the open end of the bag may be easily and quickly pleated 55 for sewing purposes, and in connection therewith improved means for sewing the same, the bag holder being so arranged that the bag may be placed in operative position for filling, after which it may be sewed and the entire mechanism 60 run on a scale for weighing the contents of the bag, after which it may be transferred to any desired position, so that a single placing of the bag in the holder accomplishes the filling, sewing, weighing and transferring, thereby eliminating a number of unnecessary operations.

I claim as my invention:

1. In a device of the class described, the combination of a base, upright supporting members, a horizontal frame carried by the upper ends of said upright supports, a shaft rotatably mounted therein, a second shaft rotatably and slidably mounted to move toward and from the first shaft, a set of pleating fingers slidably and non-rotatably mounted on each shaft, expandible springs 70

supported alternately between said fingers, the fingers of one shaft being directed horizontally toward those of the other shaft and in staggered relation therewith, and means for moving said fingers together against the action of said springs. 80

2. In a device of the class described, the combination of a base, upright supporting members, a horizontal frame carried by the upper ends of said upright supports, a shaft rotatably mounted therein, a second shaft rotatably and slidably mounted to move toward and from the first shaft, a set of pleating fingers slidably and non-rotatably mounted on each shaft, expandible springs supported alternately between said fingers, the fingers of one shaft being directed horizontally toward those of the other shaft and in staggered relation therewith, means for moving said fingers together against the action of said springs, and means for slightly elevating the bag as the movable set of fingers is moved inwardly. 85

3. In a device of the class described, the combination of a base, upright supporting members, a horizontal frame carried by the upper ends of said upright supports, a shaft rotatably mounted therein, a second shaft rotatably and slidably mounted to move toward and from the first shaft, a set of pleating fingers slidably and non-rotatably mounted on each shaft, expandible springs supported alternately between said fingers, the fingers of one shaft being directed horizontally toward those of the other shaft and in staggered relation therewith, means for moving said fingers together against the action of said springs, and means for slightly elevating the bag as the movable set of fingers is moved inwardly. 90

4. In a device of the class described, the combination of a base, upright supporting members, a horizontal frame carried by the upper ends of said upright supports, a shaft rotatably mounted therein, a second shaft rotatably and slidably mounted to move toward and from the first shaft, a set of pleating fingers slidably and non-rotatably mounted on each shaft, expandible springs supported alternately between said fingers, the fingers of one shaft being directed horizontally toward those of the other shaft and in staggered relation therewith, means for moving said fingers together against the action of said springs, and means for slightly elevating the bag as the movable set of fingers is moved inwardly. 100

5. In a device of the class described, the combination of a base, upright supporting members, a horizontal frame carried by the upper ends of said upright supports, a shaft rotatably mounted therein, a second shaft rotatably and slidably mounted to move toward and from the first shaft, a set of pleating fingers slidably and non-rotatably mounted on each shaft, expandible springs supported alternately between said fingers, the fingers of one shaft being directed horizontally toward those of the other shaft and in staggered relation therewith, means for moving said fingers together against the action of said springs, and means for slightly elevating the bag as the movable set of fingers is moved inwardly. 110

6. In a device of the class described, the combination of a base, upright supporting members, a horizontal frame carried by the upper ends of said upright supports, a shaft rotatably mounted therein, a second shaft rotatably and slidably mounted to move toward and from the first shaft, a set of pleating fingers slidably and non-rotatably mounted on each shaft, expandible springs supported alternately between said fingers, the fingers of one shaft being directed horizontally toward those of the other shaft and in staggered relation therewith, means for moving said fingers together against the action of said springs, and means for slightly elevating the bag as the movable set of fingers is moved inwardly. 120

7. In a device of the class described, the combination of a base, upright supporting members, a horizontal frame carried by the upper ends of said upright supports, a shaft rotatably mounted therein, a second shaft rotatably and slidably mounted to move toward and from the first shaft, a set of pleating fingers slidably and non-rotatably mounted on each shaft, expandible springs supported alternately between said fingers, the fingers of one shaft being directed horizontally toward those of the other shaft and in staggered relation therewith, means for moving said fingers together against the action of said springs, and means for slightly elevating the bag as the movable set of fingers is moved inwardly. 130

8. In a device of the class described, the combination of a base, upright supporting members, a horizontal frame carried by the upper ends of said upright supports, a shaft rotatably mounted therein, a second shaft rotatably and slidably mounted to move toward and from the first shaft, a set of pleating fingers slidably and non-rotatably mounted on each shaft, expandible springs supported alternately between said fingers, the fingers of one shaft being directed horizontally toward those of the other shaft and in staggered relation therewith, means for moving said fingers together against the action of said springs, and means for slightly elevating the bag as the movable set of fingers is moved inwardly. 140

9. In a device of the class described, the combination of a base, upright supporting members, a horizontal frame carried by the upper ends of said upright supports, a shaft rotatably mounted therein, a second shaft rotatably and slidably mounted to move toward and from the first shaft, a set of pleating fingers slidably and non-rotatably mounted on each shaft, expandible springs supported alternately between said fingers, the fingers of one shaft being directed horizontally toward those of the other shaft and in staggered relation therewith, means for moving said fingers together against the action of said springs, and means for slightly elevating the bag as the movable set of fingers is moved inwardly. 150

toward and from the first shaft, a set of pleating fingers carried by each shaft, the fingers of one shaft being arranged in staggered relation with those of the opposite shaft, means for supporting opposite sides of the open end of a bag when the shafts are spaced apart, means for moving one of said shafts toward the other, means for yieldably supporting said bag to permit the bag to be elevated as said opposite sides of the opened end of 10 said bag are moved together.

8. In a device of the class described, the combination of a support, a shaft rotatively mounted therein, a second shaft rotatively and slidably mounted to move toward and from the first shaft, 15 a set of pleating fingers slidably and non-rotatively mounted on each shaft, the fingers of one shaft being directed horizontally toward those of the other shaft and in staggered relation therewith, means carried by the free ends of said fingers for supporting the open end of a bag, means for locking the shafts against rotation to support said fingers in a horizontal position, means for moving one of said shafts toward the other, and means for automatically releasing said locking 20 means upon the return movement of the movable shaft.

9. In a device of the class described, the combination of a base, upright supporting members, a horizontal frame carried by the upper end of 30 said supports, a bag supporting platform

having one end horizontally pivoted to said uprights, yieldable means for supporting said platform in a substantially horizontal position, an upwardly inclined lever for oscillating said platform about its pivot, means carried by said horizontal frame for supporting the upper end of a bag with its lower end resting on said platform, and means for closing the upper end of said bag and pleating the closed end, and means for automatically elevating said bag as its upper end is closed and the pleating operation takes place.

10. In a device of the class described, the combination of a base, a supporting frame, a bag supporting platform, means supported above said platform and carried by said frame for supporting the upper end of a bag with its lower end resting on said platform, means for closing the upper end of said bag and pleating the same, means for automatically elevating said bag as its upper end is being closed and the pleating operation takes place, for the purposes stated.

11. In a device of the class described, the combination of a base, a pair of parallel supports, a series of spaced pleating fingers slidably mounted on each support, the fingers of one support being staggered to those of the other support, means for moving one of said supports toward the other support and for simultaneously moving the fingers of each support together.
